(57) **CLAIM**

The ornamental design for the emergency vehicle detector, as shown and described.

DESCRIPTION

The ornamental design is for a emergency vehicle detector having a securing feature that can secure the apparatus to a visor such as a sun visor found in many vehicles. Also shown is the emergency vehicle detector without the optional securing feature.

FIG. 1 is a front elevation view of a first configuration of the novel design according hereto;

FIG. 2 is a rear elevation view thereof;

FIG. 3 is a left elevation view thereof;

FIG. 4 is a top elevation view thereof;

FIG. 5 is a bottom elevation view thereof.

FIG. 6 is a front elevation view of a second configuration of the novel design according hereto;

FIG. 7 is a rear elevation view thereof;

FIG. 8 is a left elevation view thereof;

FIG. 9 is a top elevation view thereof; and,

FIG. 10 is a bottom elevation view thereof.
